UNITED STATES PATENT OFFICE.

JAMES A. EKIN CRISWELL, OF NEW YORK, N. Y.

MATCH.

988,246.

Specification of Letters Patent. Patented Mar. 28, 1911.

Application filed January 16, 1905. Serial No. 241,234.

To all whom it may concern:

Be it known that I, JAMES A. EKIN CRISWELL, of New York, county of Kings, and State of New York, have invented certain new and useful Improvements in Matches, of which the following is a full, clear, and exact description.

This invention relates to matches, and more particularly to matches having composite stems or splints.

The primary object of the invention is to provide matches made wholly or in part of cheap material, or material that ordinarily goes to waste; which are stronger and less liable to break and more uniform in quality than the usual wood match made from blocks or wood veneer; and which will burn longer than the usual wood match.

A further object of the invention is to provide a match that is better and more cheaply made than the usual form of match, and which may be made of material readily found in almost any locality and country, thereby permitting matches to be made where it is practically impossible to do so under the methods in ordinary practice without transporting the materials often very long distances.

With these and other objects in view the invention will be hereinafter more particularly described with reference to the accompanying drawings, which form a part of this specification, and will then be pointed out in the claim at the end of the description.

In the drawings, Figure 1 is an enlarged general perspective view of one form of match embodying my invention. Fig. 2 is a transverse section on a still larger scale. Figs. 3 to 6 show other ways of inclosing the inner core with an outer casing or cover; and Figs. 7 to 12 show in cross-section other forms of matches.

While I shall refer particularly to certain materials and combination of materials as constituting the matches, it will be understood that the materials, as well as the proportions of the materials may be changed as found most desirable and convenient.

The matches shown in Figs. 1 to 8 have an inner body or core 20, an outer covering or casing 21 and the usual igniting head 22. The inner body or core 20 may be of any suitable material. It may consist of paper pulp made from rags, straw or other vegetable fiber or waste which is converted

into a hot liquid mass in a mechanical stirrer or by other suitable means. Twenty-five parts of the pulp are mixed in a beater with six parts of broken or ground peanut shells, wood pulp or other suitable vegetable matter. The mixing is done while maintaining a high heat, and to this mixture may be added one to two parts of glue or gum-tragacanth, the mixing being continued until a thick mass is obtained. This mass may be formed into small rods by forcing the material from a cylinder or other device through small apertures or nozzles. Either before or after the rods are dry they are provided with an outer covering or casing of paper 21, which serves to prevent disintegration of the inner body or core, each thereby serving to strengthen the other and thus provide a strong and substantial stem or splint. The splints may be paraffined and provided with an igniting head 22 in the usual or in any preferred way, and the materials or the entire splints may be impregnated with the usual chemicals when necessary or desirable to prevent glowing after the flame has been blown out.

In the manufacture of the matches the splints may be made in one machine, and the matches completed in another, or the entire process may be carried out continuously where the materials constituting the matches are of such a character as to permit this. When the inner body is of a plastic or semi-plastic nature it may be forced through small apertures from a cylinder in which works a reciprocating piston or a rotary spiral or other device which gradually forces the material through said apertures. The paper for the casing is fed from reels either in the shape of a web or ribbon and is caused to be formed around the small rods of material. The splints may then be cut off the proper lengths and when necessary dried; or they may be dried or otherwise treated, cut, and then transferred to a carrier in substantially the same manner as disclosed in one or more of my Patents Nos. 716,809 to 716,829, dated December 22, 1902. The carrier then takes the matches and heads them in the usual or in any preferred manner and after the match heads are dry they are ejected and then boxed.

Instead of the cover or casing 21 being folded lengthwise of the core 20 as in Fig. 1, the cover may be in the form of a ribbon

which is spirally wound around the core as in Figs. 3 and 4; or instead of being in a single strip, the casing may be in two narrow strips of paper folded lengthwise of the core as in Figs. 5 and 6. The cover may be of paper or other inflammable material, and the matches may be made of any desired shape, whether round, square, hexagonal as in Fig. 7, triangular as in Fig. 8, or other form according to the means employed for producing them. When the core is of an adhesive nature, the cover need not have any additional adhesive substance applied thereto, except possibly at the edges of the cover or wrapper in case the edges are made to overlap.

The inner body or core may be made of wood pulp, a carbonaceous substance, peat, paper-making pulp, plaster of Paris, crushed vegetable matter, grain products as flour, nut shells, wood pulp, woody fiber, seed products as cotton seed refuse, long fibrous vegetable matter as disintegrated, shredded or crushed wood, and a suitable binder, combined as a whole or in part in any suitable proportion, and provided with a cover of paper or other material if desired.

Long fibrous materials may be used in the manufacture of matches according to my invention, some of which are weeds, grass, straw, shrubs, excelsior, shavings of wood, cornstalks, marsh weed, seaweed, plants, vegetables, fruits, vegetable matter of various kinds, as from distilleries, cotton, cactus fiber, slivers, disintegrated fibrous or stringy vegetable material, dry peat, rubbish, soil, soil loam, paper, scraps, moss, leaves, twigs, barks of trees, bagasse, stalks, flowers, seeds of sunflowers or their pulp, turf, asbestos fiber, and others. These or any of them may be treated chemically or mechanically and any of them may be combined with any suitable binding substances, or any of the materials already mentioned.

According to one method I use weeds, straw, grass, twigs, or other fibrous material named, and instead of reducing them to a pulp or pulpy condition, I tear them into shreds by a suitable picking or other machine for that purpose. The shredded material is then passed through a bath of rosin or resinous oil or other binding material combined or not with the rosin, and to this may be added in suitable quantities any of the materials mentioned. The fibrous material may be arranged in the form of a layer or web and then passed between corrugated or ribbed rollers to form long splints or rods which may be cut off the proper lengths to form match splints and the splints are then taken and the matches completed as already described or in any preferred way. In some cases when the body is made of long fibrous material, I may or may not place a covering of paper

or other inflammable body on the outside of each splint as in Fig. 9 depending on the materials used, and in any case the tubular covering may be dispensed with if desired, as in Fig. 10.

According to another method I take grasses, straw, disintegrated wood fiber or any of those fibrous materials of annual growth, many of which go to waste or other fibrous material and subject them to heat by boiling in water or by steam until the fibers are softened, but not necessarily reduced to a pulpy state. If desired lime-water may be employed to facilitate the cooking as in the manufacture of strawboard. The fiber thus treated may be mixed or combined with a suitable binding material, or other materials herein specified or their equivalents and then formed into matches. I may take straw, sawdust, shavings, paper or any suitable vegetable substances and thoroughly digest them in acids to make a vegetable pulp. Of this pulp I may take ten parts peat or moss one part, asbestos fiber one and one-half parts, and to this is added suitable binder. These materials may be combined in different proportions and may be added to others, or any of those previously mentioned may be combined with those just referred to in suitable quantities.

In Fig. 11 is shown an inner core of wood paper or other material 22, around or on each side of which is a material 23 of a plastic or semi-plastic nature when applied to the material 22 and an outer coating or casing of paper 24, wood pulp or other material. The material 22 may be in the form of sheets or a web and on each side there is formed a layer of plastic or semi-plastic material, which latter may be compressed or formed into the desired shape as the match splints are made. In Fig. 12 the outer covering is dispensed with.

If desired a paper or other covering may be fixed direct to an inner core of wood strips or woody material, or the inclosed casing may be a thin ribbon or strip of veneer having an inner core of the material mentioned; or if desired I may form a web of cotton or like material and combine with other material such as those mentioned and form them into splint rods and inclose the splints or not as already explained. Materials or any of them may be chemically treated and to any of the combinations may be added singly or in combinations such as saltpeter, acetate of copper, sal-soda, sulfide of zinc, glycerin, alum, acids, lime water, pyrolygneous acid, borax, antimony, furic acid, barium sulfate, caustic soda, eratus, bicarbonate of soda, chlorate of lime and others. As a binder for the materials or any of them I may use any suitable material or combination of materials to inclose them in a homogeneous mass so as to

vide a strong efficient and durable match stem, I may use glucose, glue, rosin, lime, flour, plaster of Paris or any suitable glutinous or resinous substance.

5 It will be understood that at any stage of the making of the matches, I may add paraffin, crude petroleum or other oils; and I may add sulfur, rosin, saltpeter, and other materials independently or mixed with 10 others when it is desirable to make the match stems or splints burn more readily.

It is desirable sometimes to color the materials either in whole or in part, and this may be done by the use of anilin or other coloring material; and where the match stems 15 have a covering of paper or like material, advertising matter may be placed on each match.

It will be seen from the foregoing that 20 various materials ordinarily going to waste may be utilized in the manufacture of matches; that cheap and inexpensive materials may be used so that matches may be made readily in those countries or localities 25 where there is a scarcity of wood; and that in using the materials herein referred to a

strong, effective and neat looking match is produced, with little or no waste.

It has not been attempted to give the various combinations of materials or their proportions as these may vary; nor has it been attempted to set forth the various methods or apparatus for the manufacture of the matches, as these will form subject matter 30 for other applications.

35 By the term "paper" as applied to the outer cover or casing it is understood that it is used in its broadest sense; and it is further understood that the matches may be in the form of match cards, or in any other 40 suitable form.

Having thus described my invention, what I claim as new and desire to secure by Letters Patent, is—

45 A match splint comprising a tube of relatively strong paper stock, adapted to secure the necessary stiffness, and a filling of relatively weak paper stock.

JAMES A. EKIN CRISWELL.
